PLASTIC CONTAINER FOR LIQUIDS

Wallace Douglas Templin, Coraopolis, Pa., assignor to
Foremost-McKesson, Inc.

Filed Aug. 20, 1973, Ser. No. 390,127

Term of patent 14 years

Int. Cl. D9—01

U.S. Cl. D9—131

FIG. 1 is a side elevational view of a plastic container for liquids, showing my new design;

FIG. 2 is a plan view thereof; and

FIG. 3 is a half section thereof on an enlarged scale.

I claim:

The ornamental design for a plastic container for liquids, as shown.
